UNITED STATES PATENT OFFICE.

ALFRED ANGAS SCOTT, OF BRADFORD, ENGLAND.

GRINDING AND LIKE MACHINE.

1,026,610.

Specification of Letters Patent. Patented May 14, 1912.

Application filed December 18, 1911. Serial No. 666,380.

To all whom it may concern:

Be it known that I, ALFRED ANGAS SCOTT, a subject of the King of Great Britain, residing at Bradford, Yorkshire, England, 5 have invented certain new and useful Improvements in Grinding and Like Machines; and I do hereby declare the following to be a full, clear, and exact description of the invention, such as will enable others skilled 10 in the art to which it appertains to make and use the same.

This invention relates to improvements in grinding machines and the like in which a rapidly rotating grinding disk or tool is 15 worked over the surface of a slowly rotating article such for instance as a cylinder of which it is desired to grind or finish the internal bore or other surface.

According to the present invention the 20 grinding or tool spindle is mounted eccentrically or offset in a quill or rigid tube, the quill being mounted in bearings in such a way that it can be turned about its own axis to adjust the amount of eccentricity of the 25 grinding spindle relative to the work-piece, the quill being at the same time capable of being traveled in a direction parallel to its axis to obtain the necessary traverse of the grinding instrument relative to the work- 30 piece.

In the preferred form the grinding spindle is mounted eccentrically in the quill at the lower end of the same while at the upper end there is a driving spindle mounted 35 concentrically in the quill and motion is imparted from the driving spindle to the grinding spindle by means of an internal connecting shaft with universal joint connections at each end.

40 The preferred form of machine is shown in detail in the accompanying drawings in which:—

Figure 1 is a sectional side view of the machine. Fig. 2 is a front elevation. Fig. 45 3 is an enlarged sectional view of the quill. Fig. 4 is a section taken on the line IV—IV of Fig. 1 while Figs. 5 and 6 are detail views in sectional elevation and plan view in partial section respectively showing on an enlarged scale the means adopted for obtaining the feed and traverse of the grinding disk or tool.

As shown in the drawings the quill 1 is mounted in suitable bearings 2 on the body 55 3 of the machine. At the upper end of the quill 1 there is concentrically mounted the

driving spindle 4. The driving spindle 4 is provided with a spline 5 so that it can pass through the driving pulley 6 and be rotated by this pulley. The grinding spindle 7 is eccentrically mounted in the quill 1 as shown more clearly in Figs. 2 and 3. The lower end of the driving spindle 4 is mounted in ball bearings 8 which take up any thrust and is connected to the grinding spindle 7 so as to transmit its motion thereto by means of an internal connecting shaft 9. This internal connecting shaft 9 is provided at each end with a universal joint 10 to the driving spindle and grinding spindle respectively. The grinding spindle 7 is divided into two parts which are connected by a helical spring 11 both parts of the grinding spindle being mounted in suitable ball bearings. The spring 11 forms a flexible connection between the two parts of the grinding spindle and so prevents any vibration being communicated from the connecting shaft 9 to the lower part of the grinding spindle. Suitably mounted between the 20 two bearings 2 of the quill is a fixed guide rod 12 which is embraced between radially arranged jaws 13 which project from an annulus 14 arranged about a boss or fixed sleeve 15 on the quill 1. Between the jaws 13 and the guide rod 12 there are arranged suitable bushes 16. It will be seen that the annulus 14 will be capable of sliding along the guide rod but at the same time will be held against rotation with the quill owing to its jaw embracing the guide rod 12. Pivotally mounted about the guide rod 12 and so as to embrace the jaws 13 there is mounted a swinging half nut 17 adapted to be adjusted by means of a suitable handle 18. Running parallel to the guide rod 12 and mounted in a footstep bearing in the lower bearing 2 there is a lead screw 19 which at its upper end bears in bearings 20 connected to the bearings 2. This lead screw 19 is 100 continuously rotated as hereinafter described.

At the bottom of the boss or fixed sleeve 15 on the quill there is cast a flange 21 having at one side a projection 22 on which is mounted the operating handle 23. The shaft 24 of the operating handle is provided with a screw thread as at 25 and at its uppermost end with a small wedge shaped piece 26. Also mounted on the boss or sleeve 15 and 11v between the flange 21 and the annulus 14 there is a further annulus 27. The annulus

14 and 27 are provided with projections 28 and 29 respectively. The projection 28 carries a swiveling eyelet 30 to which the end of the micrometer screw 31 is fixed. The 5 projection 29 carries a swiveling nut 32 in which the threaded portion of the micrometer screw 31 engages from which it will be obvious that a very accurate relative adjustment between the annuluses 14 and 27 10 can be obtained. The annulus 27 has in it a circumferential groove 33 in which the wedge like piece 26 can be caused to engage by turning the handle 23 so as to lock when desired the annulus 27 to the boss 15 and 15 therefore to the quill.

From the foregoing arrangement it will be seen that for a quick adjustment of the eccentricity of the grinding disk or tool it will be possible to slacken the wedge 26 from 20 the groove 33 and then turn the handle 26 bodily about the axis of the quill 1 which action owing to the boss 15 being rigidly secured to the quill will cause the quill itself to be turned. On the desired adjustment 25 being approximately obtained the handle 23 can be screwed so as to lock the wedge 26 in the groove 33 so as to rigidly connect the annulus 27 to the boss 15. By then turning the micrometer screw 31 a finer and very 30 accurate relative adjustment between the quill and the annulus 14 can be obtained. This annulus 14 is, as will be obvious, held rigidly against rotation owing to its jaws 13 embracing the guide rod 12. On the 35 other hand as the jaws 13 carry the half nut 17 which engages with the lead screw 19 the annulus 14 will be raised or lowered according to the direction of rotation of the lead screw 19 when the half nut is engaged therewith and therefore the quill will 40 also be correspondingly raised and lowered in its bearings 2. The half nut 17 is provided with a projecting portion 34 carrying an upstanding pin 35 which as the half nut 45 17 is moved in and out of engagement with the lead screw 19 engages against and slips past a spring pressed nose 36 mounted in the annulus 14 as shown in Figs. 5 and 6. The swinging portion carrying the half nut 50 17 also carries a projection 37 which when the half nut 17 is in engagement with the lead screw 19 lies between two stops 38 mounted on a reversing rod 39 connected to a reversing gear hereinafter described, the 55 action of the projection 27 being toward the end of the desired amount of travel of the quill to come into contact with one or other of the stops 38 on the reversing rod and so propel the same in the direction in which 60 the quill is traveling and so operate the reversing gear and change the direction of rotation of the lead screw. The amount of travel imparted to the quill by the lead screw in each direction can be limited to 65 the desired amount by the adjustment of the

stops 38 on the reversing rod 39; this adjustment being rendered possible by means of the thumb screws 40 which are screwed into the stops 38 so as to engage with the rod 39. The lead screw 19 at its upper end is provided with a bevel wheel 41 which is driven by means of suitable bevels 42 and 43 mounted on a sliding sleeve 51 carried by a continuously rotating shaft 44 driven in a manner hereinafter described. The reversing rod 70 75 75 80 85 90 95 100 105 110 115 120 125 130 39 is connected at its upper end to a bell crank lever 45 mounted upon a suitable bracket 46 on the main body of the machine. This bracket also carries a bearing for the shaft 44. On the bell crank lever 45 there is mounted a pin or roller 47 while normally pressed against this roller 47 there is a depending finger 48 provided with a nose or projection 49. The outer end of the depending finger 48 is connected by means of a suitable spring 50 to the bracket 46 so that the depending finger is normally held up against the roller 47. The bevel wheels 43 and 42 are mounted on a sleeve 51 which is slidably mounted on the shaft 44 so as to be rotated by this latter. At the outer end of the sleeve 51 there are two annuluses 52 while between these two annuluses there is located a pin 53 mounted on the second arm of the bell crank lever 45. Also hinged on the bracket 46 there is a small locking device 54 which is provided with a projection 55 which engages with, on either side, one of the annuluses 52 so as to lock the sleeve 51 in whichever position it is placed to hold one or other of the bevel wheels 42, 43 in operative connection with the bevel wheel 41 on the lead screw 19. The locking device 54 carries a small roller 56 which lies in the path of the upstanding end of the bell crank 45. In this case as the reversing rod 39 pulls down the bell crank 45 to throw the bevel wheel 42 out of engagement and the bevel wheel 43 into engagement with the bevel wheel 41 the roller 47 rides over the nose 49 on the depending finger 48 which owing to the action of the spring 40 gives the bell crank lever a sudden impulse to complete its travel. Just as the bell crank is given this sudden impulse its upstanding end comes under the roller 56 and raises the locking device 54 so that the projection 55 is free from the annulus 52 and the further travel of the bell crank 45 causes the pin or roller 53 to strike the annulus 52 and force the sleeve 51 along the shaft 44 to obtain the desired reversed direction of rotation of the lead screw 19. As the travel of the bell crank is completed the upstanding end of the same passes under the roller 56 on the locking device and allows this latter to be pulled down again under the influence of its spring 57 so as to lock the annulus 52 on the other side of its projection 55.

The workpiece such as a cylinder is suit-

ably mounted on the rotating work table 58. This work table is mounted on a head-stock spindle 59 carried in suitable bearings 60. The head-stock spindle carries a pulley 61 rotated by means of a suitable belt 62 on a pulley 63 mounted upon a counter shaft 64. The counter shaft 64 is driven from the main driving shaft 65 as shown in Fig. 1. The shaft 44 actuating the lead screw 19 is, as shown in Figs. 1 and 2, driven by a belt 66 from the counter shaft 64. This belt 66 preferably runs over guide pulleys 67 as shown. In order to obtain two speeds for the shaft 44 this shaft carries two pulleys 68 and 69 while there are two corresponding pulleys 70 and 71 on the counter shaft 64. The belt between the pulleys 69 and 71 is omitted for the sake of clearness. By mounting a suitable clutch between the two pulleys 68 and 69 either of these two pulleys can be rigidly connected with the shaft 44. The pulley 6 is driven as shown in the drawings from pulley 72 mounted on a wall bracket 73, this pulley being mounted on a shaft 74 which is driven from the main shaft 65. A suitable device for counter balancing the weight of the quill is secured thereto as shown at 75. Devices are arranged about the lower bearing of the quill and about the grinding spindle to prevent grit getting into these parts. With this object in view the quill at the bottom end is provided with a cylindrical cup 76 which works over the lower end of the lower bearing 2 and inside a cylindrical portion 77 secured to the bearing 2. At the same time the bottom end of the bearing for the grinding spindle is protected by means of a concentric piece 78.

When it is desired to grind any object the handle 18 controlling the half nut is turned to throw this half nut out of engagement with the lead screw 19. This also throws the projection 37 out of possible engagement with the stops 38. The quill can then be bodily raised up through its bearings 2 and will be held in the position to which it is raised by the counter weight. The workpiece can then be placed on the work table 58 and the quill then pulled down to the desired amount and the two stops 38 adjusted to give the desired amount of traverse or reciprocation to the quill. The handle 18 is then turned to throw the half nut 17 into engagement with the lead screw 19. The handle 23 is then turned to release the wedge 26 from the annular groove 33 and the whole quill turned around about its axis by means of the handle 23 till the desired adjustment of the grinding spindle is obtained after which the handle 23 is twisted so as to lock the quill to the annulus 27. If some finer adjustment be desired the micrometer screw 31 is rotated with the effect previously described. The

machine can then be started. On it being desired to measure by means of a limit gage or otherwise the bore of the cylinder or workpiece being treated all that it is necessary to do is to disengage the half nut 70 from the lead screw by turning the handle 18 and then raise the quill by hand. If desired the whole machine can be self-contained and a bracket provided for the pulley 72 shown in Fig. 1 as mounted in a wall bracket. At the same time the counter weight can be arranged to work down the rear of the framework or main body.

In the foregoing description it has been assumed that the longitudinal axis of the quill was vertical. The invention is also applicable to horizontally operated machines as will be seen by placing Fig. 1 on its side and it will be realized that only a few structural alterations will be necessary to bring about the desired result.

When the machine is desired for grinding the interior bores of cylinders it is of course desirable for the center of the work table to lie under and somewhat offset relative to the center of the quill. The work table may however be placed definitely to one side in cases where it is desired to grind the outside of the object which is rotated on the work table.

In a somewhat simpler form of machine the driving spindle and the grinding spindle are arranged in one part and are both mounted eccentrically in the quill. In this case naturally the pulley 6, as the grinding wheel is adjusted, tends to move away from or approach the pulley 72 or its equivalent so that it will be necessary to provide some means for automatically taking up the slack of the pulley which can be easily effected.

I declare that what I claim is:

1. In a machine of the character described, the combination of a rigid quill or tube, bearing for said tube, a tool spindle mounted eccentrically in said tube, means for driving said tool spindle, means for adjusting said tube angularly about its own axis; and means for imparting a reciprocating motion to said tube.

2. In a machine of the character described, the combination of a rigid tube or quill, bearings for said tube or quill, a tool spindle eccentrically mounted in said tube at one end thereof, a driving spindle mounted concentrically in the other end of said tube, operative connections between said driving spindle and said tool spindle and means for adjusting the tube angularly about its own axis and for reciprocating the same substantially as described.

3. In a machine of the character described, the combination of a tube or quill, bearings for said tube or quill, a tool spindle mounted eccentrically in one end of the said tube, a driving spindle mounted concentrically in

the other end of said tube, a connecting shaft between said driving spindle and said tool spindle, universal joints connecting said connecting shaft to said driving spindle and 5 said tool spindle, means for adjusting said tube angularly about its own axis, and means for reciprocating said tube in the direction of its length.

4. In a machine of the character described, 10 the combination of a rigid tube or quill, bearings for said tube, a tool spindle mounted eccentrically in one end of said tube formed of two parts, a flexible coupling between the two parts of said tool spindle, a 15 driving spindle mounted concentrically in the other end of said tube, operative connections between said driving spindle and said tool spindle, means for adjusting said tube angularly, and means for reciprocating said 20 tube in the direction of its length.

5. In a machine of the character described, 25 the combination of a quill or rigid tube, bearings for said tube, a tool spindle mounted eccentrically in said tube, a collar held against longitudinal movement on said tube, a swinging half nut mounted on said collar, a lead screw, bearings for said lead screw, means for rotating said lead screw, means for reversing the direction of rotation of 30 said lead screw at predetermined times, and means for adjusting said tube or quill angularly about its axis.

6. In a machine of the character described, 35 the combination of a tool spindle, means for supporting and driving said tool spindle, rotatable means supporting a workpiece, means for approaching and withdrawing the tool spindle and the workpiece supporting means, the one to and away from the other; and 40 means for adjusting said tool spindle and said workpiece supporting means the one relative to and in a curve eccentric to the axis of rotation of the other while the machine is in motion.

45 7. In a machine of the character described, the combination of a rigid tube or quill, a tool spindle rotatably and eccentrically mounted in said rigid tube, bearings for said tube, a lead screw, means for rotating said 50 lead screw, means for altering the direction of rotation of said lead screw, a half nut, a guide rod acting as pivotal means for said half nut, a collar on said tube held against longitudinal movement relative to said tube, 55 said collar also embracing said guide rod, an annulus embracing said guide rod, flanges rigidly secured to the annulus embracing the guide rod, and means for adjusting the flanges together with said tube or quill angularly about the axis of said tube or quill.

8. In a machine of the character described, 60 the combination of a rigid tube or quill, a tool spindle mounted eccentrically in said rigid tube, means for reciprocating said tube in the direction of its axis, a guide rod, an

annulus embracing said guide rod and encircling said tube, means for holding said annulus against relative longitudinal movement on said tube, a second annulus about said tube, a micrometer screw device, connecting said annuli, a peripheral groove in said second annulus, a flange rigidly secured to said tube, a handle, a projection on said flange carrying said handle, and a wedge operated by said handle lying in and adapted to engage when desired with the walls of the peripheral groove in the said second annulus. 70

9. In a machine of the character described, 75 the combination of a quill or rigid tube, a spindle mounted eccentrically in said tube, means for reciprocating said tube in the direction of its axis, means for the angular adjustment of said tube, a reversing rod, adjustable stops on said reversing rod, a projection connected to said rigid tube normally 80 lying between said stops, and means for simultaneously moving said projection from between said stops and for disconnecting said tube from said means for reciprocating 85 said tube.

10. In a machine of the character described, 90 the combination of rotatable supporting means for the workpiece, a tool spindle, means for moving the tool spindle toward and away from said workpiece supporting means, means for adjusting said tool spindle in a curve eccentric to the center of said workpiece supporting means, a reversing rod, stops on said reversing rod, a projection movable with said tool spindle in the 95 reciprocations of this latter and normally lying between said stops, a bracket on the machine, a bell crank mounted on said bracket and connected to said reversing rod, a roller on said bell crank, a depending finger 100 mounted on said bracket, a nose on said depending finger, a spring normally holding said depending finger against said roller, a bevel wheel connected to the means for reversing said tool spindle, a shaft at right 105 angles to the center of rotation of said bevel wheel, means for rotating said shaft, a sleeve on said shaft, bevel wheels on said sleeve, collars on said sleeve, a projection on the free end of said bell crank, a locking device 110 engaging on one side of one of the collars of said sleeve, and means on said bell crank 115 disengaging said shaft and freeing said locking device to lock said sleeve in its new position. 120

11. In a machine of the character described, 125 the combination of a tool, a lead screw for moving said tool forward and backward, a bevel wheel on said lead screw, a shaft at right angles to and in the same plane as the axis of said lead screw, a sleeve on said shaft, bevel wheels on said sleeve, a lever, means supporting said lever, means connected to said tool spindle for moving said lever in the direction of travel of the 130

tool spindle toward the end of its travel, means connected to said lever for bringing the bevel wheels on said shaft alternately into gear with the bevel wheel on said lead screw, and means for locking said sleeve in two positions.

12. In a machine of the character described, the combination of a tool spindle, a rotating screwed shaft for imparting reciprocation to said tool spindle, a bevel wheel on said screwed rotating shaft, a rotating shaft at right angles to and in the same plane as the axis of rotation of said rotating shaft, a sleeve on said rotating shaft, bevel wheels on said sleeve on each side of said first bevel wheel, collars on said sleeve, a bracket, a lever mounted on said bracket, a projection on said lever arranged between the collars on said sleeve, a hinged locking device, means on said lever for raising said locking device to unlock the same, a spring connected to said locking device for holding said device against the action of said lever, a reversing rod connected to said lever, means connected to said tool spindle for operating said reversing rod, and spring means for assisting the movement of said lever in each direction toward the end of its travel.

13. In a machine of the character described, the combination of a rigid tube, a

tool spindle mounted in said rigid tube, means for positively reciprocating said tube in the direction of its axis, means for the angular adjustment of said tube, a driving spindle mounted concentrically in the end of said tube away from said tool spindle, a pulley splined on said driving spindle, and means for throwing the means for positively reciprocating said tube out of operative connection with said tube and for freeing said tube to permit of its being bodily raised.

14. In a machine of the character described, the combination of a rotatable support for the workpiece, a tool spindle, means for positively reciprocating said tool spindle, means for adjusting said tool spindle in a curve eccentric to the center of rotation of the said work supporting means, means for adjusting said tool spindle toward and away from said work supporting means; and means for freeing said tool spindle from its positive reciprocating means to permit said tool spindle being slid away from said work supporting means.

In testimony whereof, I affix my signature, in presence of two witnesses.

ALFRED ANGAS SCOTT.
